UNITED STATES PATENT OFFICE.

ROBERT J. NICHOLS, OF THACKERVILLE, INDIAN TERRITORY, ASSIGNOR
OF ONE-HALF TO ABNER J. CHAPMAN, OF GAINESVILLE, TEXAS.

HAY STACKING AND LOADING DEVICE.

SPECIFICATION forming part of Letters Patent No. 681,337, dated August 27, 1901.

Application filed April 29, 1901. Serial No. 58,032. (No model.)

To all whom it may concern:

Be it known that I, ROBERT J. NICHOLS, a citizen of the United States, residing at Thackerville, Chickasaw Nation, in the Indian Territory, have invented new and useful Improvements in Hay Stacking and Loading Devices, of which the following is a specification.

This invention relates to certain new and useful Improvements in hay stacking and loading devices, the object of the invention being to provide means for erecting penannular stacks; and the same consists in the construction and arrangement of the parts, which includes a crane, its supporting means, and a hay-fork, as will be hereinafter set forth.

In the accompanying drawings, Figure 1 is a plan view showing the stack and the relative position of the crane thereto. Fig. 2 is a side elevation of the crane, the stack being shown in section. Fig. 3 is a perspective view of one of the bases or anchors for the braces of the mast, and Fig. 4 is a sectional view of the step for the mast.

25 In carrying out my invention I locate at a point which will be the center of the stack a block A, having a step or bearing-plate with a central perforation for the reception of a pin, which projects from the lower end of the 30 mast. The block A is sunk into the ground and carries upwardly-projecting cheek-pieces, between which there is journaled a sheave a. The mast B, near its upper end, has a sheave b and between the sheave and support for 35 the boom C steps c, so that the top of the mast will be accessible for the purpose of taking up or letting out the chain between the top of the mast and end of the boom to change the inclination of the boom, and thus 40 regulate or determine the radius of the stack. The upper end of the mast is provided with a projecting pin having an eye which receives a cotter-pin.

45 D D refer to braces or stays, which are made up of T-iron, the ends being constructed to receive plates d and e, the upper plates being bent and perforated to engage the pin at the top of the mast. The lower plates e are formed into an eye, which engages pins carried by plates f, attached to anchors E. The anchors E, for the lower ends of the braces

D, are made up of a series of slats, which are connected to metal bars, which are bent upwardly, providing trough-shaped structures, which are spiked to the ground and weighted, 55 so as to be securely held in place, said stays maintaining the mast in a vertical position.

The boom C is made up of angle-iron and to the ends are secured filling-pieces C' of the width of the flange, and through these filling-pieces and the web of the angle-iron is passed a pin for connecting the boom to the projecting pieces near the foot of the mast. The upper end of the boom is also filled out by plates c', which are bolted or riveted to the web of 65 the angle-iron, and the web and flange are cut away to provide a space in which is positioned a pulley c². The end of the boom has attached thereto a ring with eyes on opposite sides, and to the upper eye is attached 70 a chain made up of long links, the opposite end being secured to an eye attached to a ring, which is carried by the upper end of the mast. A rope is attached to the eye at the upper end of the boom and is passed through 75 the pulley of the hay-fork or grapple, and from thence over a sheave c', and from thence to a sheave b to the pulley a on the anchor-block. The construction shown permits the boom to be swung in the arc of a circle and 80 the grapple can be swung beyond the range of movement of the boom.

The grapple or hay-fork may be of any improved construction, and is provided with a guide-rope g and a rope h for releasing the 85 grapples. The guide-rope g can be used to move the boom over the point where it is desired to deposit the hay or straw.

By means of the mechanism shown I am enabled to build or construct a penannular 90 stack of any desired height or radius, and a stack so constructed has many advantages over those of the usual shapes—for instance, the hay or straw can be removed from the ends without changing its general shape, so 95 that two wagons can be loaded from the same stack at the same time. It also affords a shelter against wind for live stock, and by closing the opening it may be used as a pen. It is also obvious that there are no sharp 100 angles in which snow may lodge, and the inner part of the stack is not affected by the wind.

In building the stack with a derrick constructed as described it is only necessary to raise the fork or grapple slightly above the height of the stack, and when the stack is built the crane or derrick may be used in loading the hay or straw upon wagons. After the stack is built the boom may be swung against one of the stays and made fast thereto.

Having thus described my invention, what I claim as new, and desire to secure by Letters Patent, is—

1. In a hay-stacking device, the combination with a hay-fork, of a crane comprising a turning mast, stays for the same, a boom made up of T-iron the ends thereof below the flange having filling-pieces, substantially as shown.
2. In a hay-stacking device a crane consisting of a mast, its boom and braces, the boom and the braces being made up of T-

iron, plates secured to the ends of the boom and the braces, and a fork connected to the end of the boom, substantially as shown.

3. In a hay-stacking device a crane consisting of a mast, a boom pivoted to the mast, a chain between the end of the boom and the top of the mast, braces which engage the mast and anchors, a hay-fork connected to the end of the boom, a rope suitably guided for raising the fork, a guide-rope, and a releasing-rope attached to the fork, substantially as shown.

In testimony whereof I have hereunto set my hand in presence of two subscribing witnesses.

ROBERT J. NICHOLS.
